AXEL ULRIK WESTFELT, OF STOCKHOLM, SWEDEN.

SORTING APPARATUS FOR COINS.

1,037,568.

Specification of Letters Patent.

Patented Sept. 3, 1912.

Application filed July 8, 1910. Serial No. 571,042.

To all whom it may concern:

Be it known that I, AXEL ULRIK WESTFELT, engineer, a subject of the King of Sweden, and a citizen of Sweden, residing at 43 Bergsgatan, Stockholm, in the Kingdom of Sweden, have invented new and useful Improvements in Sorting Apparatus for Coins, of which the following is a specification.

10 The present invention relates to a sorting apparatus for coins and the like, which—unlike other sorting apparatus hitherto known—is characterized especially thereby that the coins, having been fed in upon the apparatus fall down automatically into their special compartments without any further actuation of the coins, either directly or by shaking or moving of the apparatus being necessary.

20 The invention is illustrated in the accompanying drawing, showing the present sorting device in plan view.

The body of the apparatus consists of an even and elongated plane or plate *a* and a box *b* arranged below the plane or plate and divided into a certain number of compartments. The apparatus is arranged in such a manner that the plate *a* slopes both in the longitudinal and in the transversal direction of the plate, that is, the plate has its highest point at the corner *c* and its lowest point at the corner diagonally opposite the corner *c*. The coins are fed in upon the plate at or near the highest point *c* and in such a manner that one side of the coins rest against the plate *a*.

The coins are governed by means of lists or runways *d*, the edges of the coins running on the upper surface of said lists lying at right angles to the plane or plate *a*. This surface is hereinafter called the bearing surface. Along these lists or runways there are provided a number of apertures *g* successively increasing in size downwardly in the same proportion as the diameter of the different kinds of coins to be sorted.

The feed channel *h* is arranged at the upper end of the plate *a* in such a position that the coins run in upon the plate in a direction obliquely opposite to that in which the coins run down along the plate. The coins are hereby caused to stop a moment and change direction of travel before running down along the runways, so that they will always obtain the same speed in running down. From the feed channel *h* the

coins enter at the inside of a disk or the like *j*, the lower edge of which closes tightly on the upper list or runway *d* serving to govern the coins in proper position on the upper or first list *d*. The apertures *g* for a certain size of coins is so broad that the distance between the bearing surface of the list and the upper edge of the aperture is greater than the diameter of the coin in question, but shorter than the diameter of the coins of the next size. Further, as the apertures *g* increase in size downwardly and the coins owing to the plane being inclined both in the longitudinal and in the transversal direction of the lists or runways will always engage the upper surface of the list (the bearing surface), it will be easily understood that a rolling coin will fall down just into the proper aperture. A coin of the second smallest size, for instance, thus passes over the first aperture and falls down into the second aperture (taken from above,) etcetera. Of course the coin-apertures *g* may not extend close to the list or runway *g*, but a part for supporting the coins is left between the apertures and the list. Preferably, however, a narrow slot *e* is provided in close proximity to the upper edge (bearing surface) of the list, for the purpose of preventing dust, dirt and the like from collecting on the bearing surface of the list. Such collection of dust would cause a reduction of the exact distance between the bearing surface of the list and the upper edges of the apertures or cause a jumping movement of the coin, so that the coin would pass over the proper aperture *g* and fall down into the aperture for the coins of the next size. The box below the plate *a* is, as mentioned, divided into compartments *f*, one for each sort of coins. Between the disk or channel *j* and the apertures *g* openings *k* are provided, one narrow and one broad opening for each list or runway, and below these openings a special compartment *l* is provided, which as well as the compartments *f* projects beyond the lower longitudinal edge of the plate *a*. Through these openings *k* such coins will fall down, which by any reason will be thrown into disorder and not run exactly against the runways, for instance, a coin which would obtain a jumping movement or would abut against the upper edge of another coin. All such coins, which come out of order, thus will be collect-

ed into the compartment *l*, wherefrom they may be taken out to be fed into the apparatus again.

The walls of the compartment *l*, at the 5 lower end, project at a comparatively great distance above the plane *a* so as to catch coins, which eventually jump or roll over all the lists and openings *k*. The coins passing properly from the channel *j* run 10 along the first list and fall down into their respective apertures *g*. The coins which immediately pass over the first list or runway are engaged by a spring obstructing member *m* and are thrown by this member 15 against a shoulder *n* on the second list or runway and will thereby be governed into proper position on the said runway and fall down into the apertures adjacent thereto. The coins, which pass also over the second 20 list are engaged by a second spring obstructing member *v*, which throws the coins against a shoulder *p* on the third list or runway and causes them to run down along said runway. From the upper end of the 25 lists to the coin-apertures the bearing surfaces of the two upper lists or runways are narrower than the thickness of the thinnest coin, so that, if two coins are lying against each other, the over-lying coin may slide 30 over the under-lying one and the list supporting the last mentioned coin, and pass to the next list below. The coin-apertures are longitudinal in the direction of movement of the coins and the transversal edges of 35 said apertures are oblique, in order to prevent the coins from passing over their special apertures.

Having now particularly described and

ascertained the nature of my said invention and in what manner the same is to be performed, I declare that what I claim is:—

A sorting apparatus for coins comprising a plate having longitudinal and transverse inclination, a plurality of raised runways formed with the plate and lying parallel to the longitudinal axis of said plate, means for introducing coins to the runways in a direction obliquely opposite to the longitudinal inclination of the plate, a series of coin apertures spaced apart, adjacent to said runways increasing in their respective sizes toward the lowest point of said runways and having oblique transverse edges, a receiving hopper on said plate, openings through said plate between the hopper and graduated openings to deflect from the runways disordered coins, spring obstructing members disposed at right angles to the upper ends of the runways between the hopper and said openings to guide the coins 60 selectively into runways appropriate to their sizes, the bearing surfaces of the two upper runways being narrower than the thickness of the thinnest coin, to permit an overlying coin to slide over the underlying 65 coin and pass to the next list, shoulders forming a continuation of the runways to receive coins deflected by the spring obstructing members.

In testimony whereof I have signed my 70 name to this specification in the presence of two subscribing witnesses.

AXEL ULRIK WESTFELT.
